METHOD OF CLEANING BOILERS

Application filed June 24, 1927. Serial No. 201,268.

(GRANTED UNDER THE ACT OF MARCH 3, 1883, AS AMENDED APRIL 30, 1928; 370 O. G. 757)

My invention relates broadly to methods of cleaning boilers of stationary or moving steam power plants and more particularly to cleaning boilers installed on ships and which have combustion chambers lined with refractory material which must be kept dry at all times.

The object of my invention is to provide a method that will greatly reduce the time consumed by the present methods of cleaning boilers and prevent any direct or indirect injury thereto, and the frequent use of which will increase the efficiency and prolong the useful life of the boiler. With the methods now in use it has been necessary to remove the side casings of the boilers, the soot cleaning doors and baffles, but with my invention no part of the boiler need be removed. The usual prior method is to manually clean away the soot and solid combustion deposit, that has collected to a thickness of from two to six and more inches around the external surfaces of the lower drum of the boiler and between, above and below, the tubes, by means of a brush or other instrument. This method is not only expensive but usually consumes several weeks for a complete cleaning of a boiler. But with my method one man and one apparatus for the practice of said method may clean such boiler in a day, or two men and two such apparatus, one for each nest of tubes, may accomplish this work in half a day, far better than the same may be otherwise done. Furthermore, from the natural construction of the boiler, it is practically impossible to reach every point around the pipes and clean the combustion deposit therefrom by any manual means heretofore employed.

Steam or compressed air, with or without sand, will not efficiently remove said combustion deposit; while such sand blast in the hands of other than the most skilled operator is quite likely to unduly wear, or cut through, the boiler tubes, especially where said de-

posit is of variable thickness, as it usually is, and the difficulty of distinguishing, under ordinary working conditions, when said deposit has been cut-through at any place and when such sand is cutting into any boiler tube.

Heretofore the custom has always been to keep liquids away from the combustion chambers of boilers and the parts thereof exposed in such chamber. Such custom obviated liquids injuring and disintegrating the refractory linings of such chambers, as well as corrosion, pitting, deterioration and shortening of the life of the boiler and its metallic parts occasioned heretofore by acid or other formations caused by the reaction of said liquid, even though it be water, upon said deposit; but in spite of said long custom I have discovered that liquid may be so used without harmful result, and that my method removes said deposit before any such injurious reaction may occur, as well as washes the surfaces from which it removes said deposit to insure that no harmful results may occur.

I have likewise discovered that the constituents of said combustion deposit vary with the fuel used and the conditions under which it is used.

A number of tests made of said deposits from different fuels combusted under different conditions disclose the following variations in the constituents of said deposits:—

An ash content varying from about 40 per cent to about 70 per cent of the mass; a volatile carbon content varying from about 30 per cent to about 62 per cent of the mass; and a content of water soluble constituents varying from about 3 per cent to about 20 per cent of the mass. All of the constituents that I have found in said deposits are finely divided and intimately commingled in the mass.

Other samples may vary further and include other substances; and all contain more or less sulphur and other substances which set up strong reactions, very injurious to

metal, when associated with water or other like liquid, and which substances are classed above as water soluble.

As a part of or contributing to my invention I have likewise discovered that by creating internal stresses in said combustion deposit it may be readily fractured into relatively small particles by an external stress applied to said internal stressed deposit; that said fracture may be accomplished more quickly by increasing said internal stresses at or about the time of said application of said external stress; that liquid may be applied to said deposit so as to create each of the aforesaid stresses; that when liquid is so applied to said deposit its water soluble constituents in the affected area of said deposit are quickly liquefied and washed out forming a multiplicity of interstices in said area of deposit; that said evacuated interstices form channels for the entrance, and quick transmission of the effects, of said liquid to a substantial depth throughout said affected area of said deposit; that one of the effects of liquid upon said mass is that its water-absorbent constituents absorb said liquid; that said evacuated interstices increase the area and rate of said absorption; that said absorption expands the water-absorbent constituents of said mass; that said expansion sets up internal stresses in said affected area of said mass; that part of said mass is relatively brittle and non-elastic; that said internal stresses may substantially fracture some samples of said mass in the area kept supplied, by said evacuated interstices and otherwise, with said liquid for a sufficiently long period, but that when said affected area is subjected to the external impact of the liquid its fracture is thereby facilitated, as well as assured even when said mass, in whole or in part, may be of such character as may not be ultimately fractured by said internal stresses.

I have further discovered that said external stress on said deposit, through the channels of said evacuated liquid filled interstices, transmits said external stress in part to the interior of said mass, where the force of said impacted liquid suddenly accelerates the rate of absorption of the water-absorbent constituents of said mass and thereby substantially increases their expansive stress upon said mass affected; that said impacted liquid also imparts its stress to the non-absorbent constituents of said affected mass and thereby, and otherwise, substantially augments the internal stresses to which said affected area of the mass was subjected before the application of said external stress; that said internally transmitted part of said external stress is usually the first supplement to be applied to said initial internal stress, and the same continues as long as said external impact continues, while said further supplemental inter-

nal stress due to said further expansion is the culminating internal stress, that said culmination and said other internal stresses are continued as long as said external stress is applied; that said stresses thus applied, and continued to the extent necessary, readily, quickly and efficiently fracture into relatively small particles that are incapable of being retained upon the round as well as angular surfaces upon which they were deposited, and which may be readily conveyed by the spent liquid to a collecting point and thence transmitted even by a hose to a place of disposal, all with little manual effort and substantial speed.

In former boiler cleaning, by a blunt instrument which was frequently used to chip off said deposit, many blows were delivered upon the metallic parts of the boiler which tended to crystalize the same and shorten the life of the boiler; but with my invention substantially no vibrations are produced in the boiler parts and hence no crystallization results, or is contributed to, from the use of my invention, as the impact of the liquid produces no injurious vibrations.

In the method I have developed it is only necessary to allow the boiler to cool down and to have the fire box cleaned out when the work of cleaning the boiler may be started.

Further objects of my invention will appear more fully hereinafter as the description of the method is developed.

My invention consists substantially in the method and the various steps associated therewith as will be more fully hereinafter set forth, and finally pointed out in the appended claims.

Reference is to be had to the accompanying drawings forming a part of this specification in which like reference characters indicate corresponding parts throughout the several views and in which:

Figure 1 is a view of one of the many types of apparatus by which my method may be applied to an inverted V-type boiler, which is shown partially in section, the right hand nest of tubes 3, drum 1 and wall 5 being each broken away,

Figure 2 is a sectional view of a portion of the shield and the method of mounting the trough upon the boiler,

Figure 3 is a modification thereof;

Figure 4 is a sectional view of the packing strip,

Figure 5 is a view of my preferred form of clamping device,

Figure 6 is a view of the sprayer valve and nozzle,

Figures 7, 8, and 9 are views of the tips of the different nozzles that I have used to wash the masses of combustion deposit out of the more inaccessible places around the base of the tubes.

Referring to Figure 1, numerals 1 and 2

represent a lower and an upper boiler drum respectively of an inverted V-type water-tube boiler that are connected together by the usual tubes 3. The boiler has been shown in section to more clearly show the method of the operation but it is to be understood that in actual practice it is not necessary to remove any of the boiler's parts to practice the 10 said operation of cleaning since the entire apparatus is introduced within the fire chamber through the access door 4. A portion of the lower drum next to the firebrick 5 is cleaned by scrubbing with steel wool or a wire 15 brush until there is a clean surface along the drum between the tubes and the firebrick.

A large canvas shield is then hung from a point near the upper ends of the tubes 3 and secured at the lower end to the boiler along 20 and upon the polished strip in a manner to be hereinafter described, so that all associated parts of said boiler above said strip become, during the cleaning operation, a part 25 of said shield.

Referring to Figure 2, numeral 6 represents a canvas trough that constitutes the lower portion of the canvas shield above referred to. The lower edge of the canvas shield is clamped within a packing member 30 7, shown in detail in Figure 4. This packing member is placed along the clean strip between the boiler and the firebox and is held rigidly in position by means of clamp 7a shown in detail in Figure 5.

At the lower portion of the canvas trough are a plurality of outlet tubes 8 that carry away the used water and waste material constituting the cleanings from the boiler. The 40 tube or tubes 8 that are unattached to the run-off pipe or pipes, that pass through door 4, are plugged as shown at the left of Figure 1.

Referring particularly to Figure 3, I have shown a metal trough 9 to which the canvas shield is secured in any manner sufficient to insure a water tight connection between the 45 trough and the shield. Upon this trough is mounted a packing strip similar to that to be described with reference to Figure 4. The mounting is practically identical with that 50 of the trough shown in Figure 2.

Referring particularly to Figure 4, the packing member consists of a plurality of U-strips 10 between which is clamped one edge of the metal or canvas trough 11 which is firmly held in position by means of bolts 12. Within the channel of the outer U member is a flexible packing strip 13 of rubber or like material. It will thus be seen that when 60 any pressure is exerted against the boiler by the packing member a water tight connection is obtained.

It is to be understood that any clamping means that will secure a water tight connection between the packing strip and the boiler 65 is sufficient. However, I have found that

with the types of boilers upon which my invention has been tried, a flexibly adaptable clamp of the form shown in Figure 5 is easily adaptable to the varying slopes between the tubes and the boiler lower drums, as well as to the warping tendency of said tubes due to the high heat and internal pressure to which they are subjected.

The clamp consists of two elements 15 and 16, having semicircular grooves near the outer end and adapted to fit varying sizes of tubes. Between the straight portion of each clamp there is initially pivotally mounted a threaded member 17 that carries a threaded screw 18 in its lower end. When the clamping elements are placed around the tubes 3 said pendent members 17 may each be advantageously radially positioned about their pivotal connections to each of their respective clamping elements 15 and 16 to 75 properly position their respective screws 18 to most efficiently engage the channels of U-member 10 whereby said screws 18 may, when tightened against member 10, position and retain the adjacent edge of shield 6. The several clamping units may then be rigidly clamped in position by means of bolts passed through the holes 19 and 20. The tip of each screw 18 when placed in the channel of the U-member 10 shown in Figure 2, may thereby 80 secure in position the removable shield 6 even when some of the screws 18 inadvertently do not press against the web of said U-member 10; but in such contingency the 85 rigidity of member 10, between the screws 18 that do bind against said web, will still exert sufficient tension upon the rubber strip 13 to form a water-tight union between it and said cleaned surface of drum 1 even at points 90 where a screw 18 inadvertently should not be exerting tension against the web of member 10. It will thus be seen that the packing 100 105 110 115 120 125 130 135 140 145 150 155 160 165 170 175 180 185 190 195 198 200 205 210 215 220 225 230 235 240 245 250 255 260 265 270 275 280 285 290 time during which the boiler need be out of commission for such cleaning; and the lesser cleaning cost and longer life of the boiler being substantially less than the higher fuel cost of, and liability due to, inefficient operation of the boiler; jointly and severally invite the frequent cleaning of the boiler with my invention.

Liquid at atmospheric temperature, applied as aforesaid, will accomplish the removal of said deposit in time, but by increasing said temperature substantially above atmospheric temperature the rate of said removal of said deposit is substantially increased.

In the practice of my invention it has been found that water heated to a temperature of about 190 degrees and placed under a pressure of about 80 pounds per square inch gives satisfactory results when employed with my method which is very quick, efficient and harmless when no water is applied to the refractory linings which are usually in the form of fire-brick work and indurated plastic work which are readily deteriorated thereby. Such work, when wet, requires long periods of the application of a moderate continuous heat to dry out before the same can be efficiently used; and if wet by the waste water, which usually contain sulphurous and other acids, said drying out leaves said acid effects. For this purpose I supply the hot fresh water through a flexible pipe 21 that is led through the access door 4 and terminates in a sprayer 22. Attached to the sprayer is a nozzle 23 that may have the various tips shown in Figures 6 to 9 to direct the liquid into the more inaccessible places about the tubes.

The liquid is applied by hose 21 to the deposit to be removed, as large an area thereof as may be desired being wetted, considering that the removal by impact of said liquid will cause surplus and splashed liquid to keep adjacent areas of said deposit well wetted. This liquefies the water-soluble constituents of said deposit, as well as causes the absorption and expansion of the water-absorbent constituents of said deposit, and said expansion to create internal stresses in the affected areas of said deposit. The application of further water, usually surplus or splashed liquid, will wash said liquefied constituents of said deposit out of the interstices where they were liquefied and keeps said interstices filled with cleaner liquid which is more readily absorbed by the water-absorbent constituents of said deposit as said cleaner liquid does not tend as much toward stoppage of the pores of said water-absorbent constituents of said deposit.

Where said deposit fills the horizontal and vertical spaces between the tubes 3, as it usually does for substantial areas above drum 1, the nozzle having the opening at its tip

may be manually pressed at a downward angle against the adjacent face of said deposit, whereby the heretofore described actions and reactions of absorption, liquefying, washing out, expansion, fracture and washing out of said deposit in a limited area adjacent the tip of said nozzle by the impact of the liquid it discharges in the direction of its longitudinal axis, and whereby said nozzle will be quickly imbedded, to the extent of its length, into said deposit with relatively slight manual pressure. By rotating said flat nozzle about half of a turn throughout said operation the area of each hole will be increased. Thereupon, said nozzle may be withdrawn and other holes successively likewise formed until the face of said deposit is honey-combed with such holes, which are formed therein a distance apart dependent upon the apparent absorbent character of said deposit. While adjacent holes are being formed some of the liquid discharged therefrom is replacing to some extent the liquid left in adjacent formed holes, said replacement being cleaner and more readily absorbent liquid.

While said deposit is being thus honey-combed the liquid in the formed holes is being absorbed by the liquid absorbent constituents of said deposit in an area surrounding each hole, said absorption being directly as well as through the interstices evacuated by the liquefied constituents of said deposit in said area. Said absorption causes expansion of said liquid absorbent constituents of said deposit and internal stresses in said affected area of said deposit.

When said face of said deposit, or any desirable area thereof, has been so honey-combed, a nozzle, preferably with lateral openings either 25, 26 or 27, is then successively inserted into such formed holes, preferably in the order of their formation, and rotated back and forth about a half turn throughout said insertion and removal, whereby the laterally impacted preferably hot liquid will rapidly complete the disruptive action, initiated by said expansion, and wash out the fragments of said deposit in said affected area progressively as said nozzle is so moved throughout the extent of each of said holes. I have found that a nozzle with an opening only at its point will accomplish this work, but it requires a longer time, and the holes must be spaced closer together.

Some of the impacted liquid will be projected above the upper layer of tubes 3 and onto shield 30 when said nozzle breaks through the upper surface of said deposit; as well as when moistening, and then impacting water upon, the deposit upon said upper layer of tubes 3. Such liquid as is not absorbed by said deposit on shield 30 will drain down said shield. Said liquid not absorbed by said deposit on tubes 3 will drain down

the upper surface thereof forming pools in the depressions therein. Such drained liquid as reaches the region of the point of union between drum 1 and shield 30, Figure 5, will there form a pool for absorption into the adjacent deposit and for draining into shield 6 through an opening or openings that may exist, or be formed, through said deposit.

10 Said shield 30 is a usual part of said water-tube boilers and normally confines and directs the combusted and combusting products, coming through each nest of tubes 3, towards and to the stack. In such normal 15 function said shield 30 has formed thereon said deposit, in a layer thinning toward, and in spots near, its top, causing said shield 30, over each nest of tubes 3, to become overheated in the areas occupied by said deposit. Such overheating tends to weaken and buckle shield 30, as well as to ignite any oil that may drip, or dust that may collect, upon the exterior surface thereof, and to thus endanger the vessel or structure containing such 20 boiler. Said tendencies are obviated by the removal of said deposit at frequent intervals, which removal my invention also most economically and efficiently accomplishes concurrently with the removal of said deposit 25 from each of the nests of tubes 3.

In my invention said shield 30 not only causes the impacted liquid from said nozzle, necessary to moisten, wash out, expand, fracture and wash off said deposit therefrom, to 30 be drained, with the sludge, onto the lower portions of the shield which I form of a part of water drum 1, and the supplemental temporary shield 6 which I attach thereto; but said shield 30 serves the further function 35 of catching and draining, ultimately into said shield 6, said liquid accidentally as well as necessarily projected above the upper layer of each tube nest 3 in the operation of cleaning the boiler.

40 It is therefore apparent that said shield 6 functions as the flexible supplemental and temporary removable lower portion of, and is of smaller area than, the much greater area of shield afforded in my invention by the 45 permanent shield 30, removable shield 6 and the surface of drum 1 between the adjacent edges of said shields 6 and 30; and that my invention causes and requires said shield 30 and said surface of drum 1 to serve the 50 aforesaid additional functions foreign to their normal uses, and in violation of the heretofore prevailing custom of keeping liquid from the fireside of boilers with their usual refractory material linings and the metal 55 parts which are usually pitted, corroded and deteriorated heretofore by acid reactions caused by the wetting of combustion deposits thereon.

60 Thus, in my invention, inadvertent or accidental diversion of the liquid impacting

nozzle occasions no injury to the refractory linings, when present, as said members 30, 1 and 6 function together as a shield of such ample proportions as to catch practically all possible discharge of said nozzle. This 65 enables a spare boiler to be cleaned while the vessel is at sea, or even during a storm, without wetting or injuring the refractory lining by such moisture. By its flexible construction said shield also prevents injury to said 70 refractory material in placing or removing said shield 6, which also prevents injury to the operator or operators who may be thrown off their balance by the motion of the vessel and against shield 6 and its edges.

The nozzle may be moved closer to, or farther from, as well as at any angle to, said deposit to obtain the best results with different shapes as well as characters of said deposit, and, when the most efficient distance 80 or angle of impact is not apparent to the operator from initial inspection, the operator's observance of the effect of the impact on a given area will enable him to change the distance or angle of impact, when required, to 85 obtain the quicker fracture of said deposit. When continuous impact upon one area does not readily produce fracture of the thus impacted area the operator should change said impact to successive impacts upon said and 90 some other area of said deposit, and each of said successive impacts upon the same area may be at a different angle or distance, as such successive impact stresses will more readily fracture certain characters of such 95 deposit. Also, some areas of such deposit will require, for quickest fracture, that each impact be commenced at one distance or angle and continued at progressively different 100 distances or angles.

The liquid deflected from other impacts usually furnishes ample washing of the surfaces from which said deposit has been removed, but when it is observed that any such surface is insufficiently washed it may then 105 be impacted and washed directly by said nozzle discharge.

It will also be noted that in my invention one of the fundamental purposes is to apply and impact the liquid in whole, or in substantial part, from such direction that the deposit, to which said liquid is to be applied and impacted, lies between the applying and impacting nozzle and one of the shield portions 1 and 30 so that such, or like, fixed 115 metallic parts of the boiler as thus receive said liquid will not be injured thereby, and whereby the parts liable to such injury or impairment need receive none of said liquid; and that said flexible removable shield 6, or 120 its equivalent, may receive only the drainage therefrom, and practically no necessary direct or deflected impacted liquid, to avoid any splashing of said liquid from said shield 6 onto the refractory lining.

Practically every different design of boiler will require a different apparatus in order to carry out my invention in its cleaning. It was necessary to overcome existing long 5 established custom and prejudice against the use of liquid on the fire-side of boilers, and to develop my method of cleaning the same independent of any type of apparatus for its execution.

10 The nozzle shown in Figure 6 is that of the diamond type 24 that is used for all direct work. The nozzle shown in Figure 7 has the diamond type point 24 with a plurality of side slots 25 directing the liquid from the 15 sides of the nozzle.

The nozzle shown in Figure 8 is similar to the one shown in Figure 6 except that one of the sides of the diamond point is sheared off on one side, as at 26, to direct the flow 20 of liquid to one side. Also in the sides of the nozzle tube are a plurality of holes 27 that serve the same purpose as the side slots shown in Figure 7. The nozzle shown in Figure 9 is open ended and is used for direct 25 washing of the larger surfaces between the boiler tubes.

Each of the nozzles is formed of tubing, the sides of which are flattened throughout the major portion of its length, as shown in 30 Figure 6, in order to readily introduce the nozzle, to the extent of its flattened length, into the horizontal as well as vertical spaces between the tubes 3 of each tube nest, as well as to obtain a greater volume of liquid flowing 35 at high velocity in a flattened stream than would be obtainable from a round nozzle of a size readily introducable into said spaces.

Said flat stream of liquid, ejected by said 40 flat nozzle, may be sprayed over a given area quicker, when the long axis of said stream is substantially parallel with the surface to be wetted thereby, than by a round stream of said limited size, while its greater volume of discharge of impact liquid substantially 45 lessens the time in which said deposit may be moistened, liquefied in part and washed out, absorb, expand, disrupted and washed away by said impacted liquid.

Said combustible deposit soon forms in 50 constant use of the boiler and in thicknesses varying from two to more than six inches, especially over the drums 1 and lower part of each nest of tubes 3, where, before my invention about ninety per cent of the failure 55 of such tubes occurred.

The speed and ease with which my invention cleans a boiler invites its frequent use and which prolongs the efficient life of such boilers from one to two years longer than 60 when my invention is not used.

The method that I have found most efficient is to allow the boilers to cool and have the fire removed from the fire box. As soon as the temperature of the fire box has lowered 65 sufficiently to permit an operator to work

therein, the shield and trough are inserted through the access door. A strip is then cleaned along the lower drum 1 of the boiler just above the sloping top of the fire-brick wall 5 and below the tubes 3; and the trough 70 is mounted, with one edge in contact with said cleaned strip, in the manner above described forming a water tight connection between the boiler and the packing member. The shield is then hung from the upper ends 75 of the tubes.

After the shield and the trough have been secured in position and the liquid or water conduit is led through the access door. The operator then works from above the shield 80 and inserts the nozzle between the tubes and turns on the water. Beginning near the top of each tube he follows the spaces between the tubes down to a point in close proximity to the lower boiler drum 1. By the use of this 85 hot fresh water, I have found that the deposits that collect upon the tubes and more particularly that which solidifies into a compact mass near the base of the tubes of the boiler 1 is disintegrated to a sufficient fine-ness to be carried from around and between the tubes into a trough and through the outlet conduits.

I have tried many kinds of shields, but 90 said flexible lower removable shield 6 has been found most efficient, enables the operative or operatives to work expeditiously and with safety in the close quarters where the same must be used, and especially when, to expedite the work, a separate shield 6 and one or more additional operatives are simultaneously employed for each nest of tubes 3, wherein, as well as in the use of but one shield, such flexible shield 6 yields readily to, and 95 may be displaced conveniently by, the bodies of the operatives at points where the same is not then being used as a liquid and sludge shield. Said temporary displacements of said shields 6 afford ample working space for the operatives and the nozzles and their hose, besides affording as safe gangway for the operatives substantially the whole area between the upwardly-converging water-tubes 3, and contact with said flexible shields 6 affords the 100 operators timely warning that harder substances are being approached.

An unflexible and unyielding shield 6 could not be employed without sacrificing the aforesaid advantages, and must be made in small sections, to get them into and out of the door 4, with liability of leakage in each joint between such sections, besides affording less room for the operatives, more liability of injuring them or the refractory lining by accidental contact therewith, and precludes 105 more than one such rigid shield being used in the same combustion chamber at the same time.

By this method it will be seen that by applying hot water under pressure in the man- 110

15 It will be understood that the above description and accompanying drawings comprehend only the general and preferred embodiment of my invention and that minor detail changes in the steps of the method or 20 of the appended claims without sacrificing any of the advantages of my invention.

In my co-pending application, Serial No. 201,267, I claim the apparatus herein disclosed by which may be practiced the method 25 herein claimed.

28 herein claimed.
The invention herein described may be
manufactured and used by or for the Gov-
ernment of the United States for govern-
mental purposes without the payment to me
30 of any royalty thereon or therefor.

Having thus described my invention what I claim is as follows:

1. The method of cleaning boiler tubes which includes the steps of washing the solid deposits therefrom by impacting a heated liquid thereon at an angle and preventing said liquid from contacting parts that might be damaged thereby.

2. The method of cleaning boiler tubes
40 which includes the steps of washing the solid
deposits therefrom by means of a heated sol-
vent liquid under pressure impacting there-
on in a volume sufficient to accomplish the
removal of the deposits without forming
45 harmful reactions between said deposit and
liquid, and preventing the washing liquid
from contacting parts that might be dam-
aged thereby.

3. In the operation of cleaning the combustion deposit from boiler parts, the method including the following steps; introducing liquid under pressure into the fire-side of a boiler, applying said liquid to said deposit and obtaining a reaction therefrom, impacting further liquid upon portions of the deposit to which liquid had been applied, and preventing the liquid from contacting parts that might be damaged thereby.

4. In the operation of cleaning the combustion deposit from boiler parts, the method including the following steps; introducing liquid under pressure into the fire-side of a boiler, applying said liquid successively to relatively small areas of said surfaces to be cleaned, and keeping said liquid from contact

with such associated parts as may be injured thereby.

5. In the operation of cleaning the combustion deposit from boiler parts, the method including the following steps; introducing liquid under pressure into the fire-side of a boiler, applying said liquid successively to relatively small areas of said surfaces to be cleaned, keeping said liquid from contact with such associated parts as may be injured thereby, and collecting and conveying said spent liquid and sludge from said boiler. 70 75

6. In the operation of cleaning the combustion deposit from boiler parts, the steps in the method thereof consisting of expanding the expansible constituents of said deposit, and keeping the expanding agency from contacting parts that might be damaged thereby.

7. In the operation of cleaning the combustion deposit from boiler parts, the steps in the method thereof consisting of expanding the expansible constituents of said deposit successively in relatively small areas of said deposit, successively impacting said expanded areas, and keeping the expanding and impacting agencies from contact with the associated portions of the boiler liable to be injured thereby.

8. In the operation of cleaning the combustion deposit from boiler parts, the steps in the method thereof consisting of creating an internal stress in said deposit, subjecting the stressed deposit to an external stress by substantially impacting the same with a jet of the medium creating said internal stress, and maintaining said medium out of contact with other parts of the boiler liable to be impaired thereby.

9. In the operation of cleaning the combustion deposit from boiler parts, the step in the method thereof consisting of successively creating an internal stress in said deposit, successively subjecting the stressed deposit to external stresses, and keeping the stressing agency from contact with associated portions of the boiler liable to be injured thereby.

11. In the operation of cleaning the combustion deposit from boiler parts, the steps in the method thereof consisting of manually cleaning a part of the boiler below parts to be cleaned, applying a liquid shield to said

part, and applying liquid to said parts to be cleaned.

12. In the operation of cleaning the combustion deposit from boiler parts, the steps in the method thereof consisting of applying a liquid shield below parts to be cleaned, applying liquid under pressure to the deposit to be cleaned from such direction that said deposit lies between the liquid to be applied and said shield, whereby said shield may receive substantially no direct application of said pressure liquid.

BERIAH M. THOMPSON.
